EXPANSIVE BIT.

1,165,854.

Specification of Letters Patent. Patented Dec. 28, 1915.

Application filed June 3, 1915. Serial No. 31,975.

To all whom it may concern:

Be it known that I, HENRY O. DAVIS, a citizen of the United States, residing at Gloucester, in the county of Essex and State 5 of Massachusetts, have invented an Improvement in Expansive Bits, of which the following is a specification.

The ordinary expansive bit, or wood auger, which has been in general use for 10 many years, comprises a main auger having a fixed blade thereon, and a second blade which is mounted for radial adjustment in a slot in the shank of the auger and is adapted to remove a chip beyond that removed by 15 the main auger. While these bits are suitable for boring holes approximately 2½ in. in diameter, and less, if the wood is hard, or if it is attempted to bore a hole of greater diameter, the strain on the adjustable blade 20 is so great at the point where it extends beyond its seat, that it is liable to be broken off at this point. Moreover, the strain on the bit, at the side from which the blade projects, is much greater than the strain at 25 the other side, so that there is a tendency to cause the bit-shank to be tilted out of alignment, and, when this occurs, the danger of breakage is greatly increased, and the boring of a uniformly round hole is pre- 30 vented.

The object of my invention is to provide a form of expansive bit, with which holes may be bored which are of considerably greater diameter than the holes which it has 35 previously been possible to bore, with the ordinary expansive bit, above referred to, without breaking it, and with which, at the same time, will operate in the manner of an ordinary wood auger, in that it will bore a 40 hole to the full size desired from the beginning of the operation to the end, and incidentally will obviate the tendency to cause the bit-shank to be tilted out of line. I accomplish this object, primarily, by providing 45 the shank of the bit with a pair of blades, at opposite sides thereof, which project unequal distances radially from the center, and by arranging said blades so that the cutting edge of the shorter blade will be held a short 50 distance, equal the depth of a chip, in advance of the edge of the longer blade, so that the longer blade will only engage the wood outside the path of the end of the shorter blade, thereby equalizing the strain 55 on the blades, so that neither will be unduly

strained, and preventing the strain of cutting the wood, beyond that cut by the main auger, from being placed entirely on one blade.

For a more complete understanding of my 60 invention, reference is made to the accompanying drawing, in which,

Figures 1 and 2 are elevations of a bit or auger made according to my invention. Fig. 3 is a longitudinal, sectional view on 65 the line 3—3 of Fig. 1. Fig. 4 is an end view of the bit.

As shown in the drawing, the shank *a*, of the main portion of the bit, is provided with the usual fixed cutting blade *b* at its lower 70 end, and with the usual feeding worm *c*.

According to my invention, I provide a pair of blades *d* and *e*, which are similar in form to the ordinary adjustable blade employed in the common form of expansive 75 bit, except that the blade *e* is of substantially greater length (approximately one-third greater, at least) than the blade *d*, which is of usual length. I further provide means for clamping said blades at opposite 80

sides of the shank, and for this purpose dovetail shaped grooves are formed in the opposite sides of the shank, the bottoms of which are flattened, to provide flat seats 85 for the inner sides of said blades *d* and *e*,

under-cut shoulders *f* and *g* being formed at the sides of said grooves next the blade *b*, and under-cut shoulders *h* and *i* being formed at the opposite sides thereof. The 90

edges of the blades, which carry the cutting edges, are formed to fit against the upper side of the blade *b* and are inwardly inclined to fit against the shoulders *f* and *g*, while the opposite edges are outwardly inclined, to receive correspondingly inwardly inclined edges of a pair of clamping plates *j* and *k*, respectively, the opposite edges of the latter being outwardly inclined, to engage the shoulders *h* and *i*. A clamping 95

screw *m* is arranged to pass through plate *j* and the shank *a* and to be threaded into the plate *k*, so as to draw said plates together and cause the blades to be firmly wedged therebetween and the shoulders *f* and *g*. Both blades are thus firmly clamped 100 on the shank of the bit by the single clamping screw.

As best shown in Figs. 2 and 3, the shoulder *f* is somewhat lower, or nearer the 105 threaded end of the bit than the shoulder *g*, 110

this difference preferably corresponding, approximately, to the pitch of the threads on screw *c*. As a result, when the blades are placed in position, the cutting edge *d'*, of the shorter blade *d*, will be held in advance of, or at a slightly lower elevation than the cutting edge *e'*, of the longer blade *e*, said edge *d'* being held approximately midway between the edge of the blade *b* and the edge *e'*, at the point where said edges *d'* and *e'* leave the side of the shank *a*.

The blades *d* and *e* are so formed and the seats in which said blades are held are so located, that their cutting edges extend 15 downwardly as they extend outwardly, to such an extent that the outer ends of the blades *d* and *e* will be each carried at approximately the level of the fixed blade *b*, or in the plane of its path, so that the fixed 20 blade and the longer blade will cut through the wood at the same time. It may be noted in this connection, that with a boring tool of this type, it is practically essential that all the blades operate at approximately the 25 same level, or closely adjacent the level of the shank end of the feeding worm, otherwise the hole would not be bored through the wood, throughout its entire diameter, by the time the worm passed therethrough, and 30 became ineffective to feed the tool.

In practice the longer blade *e* will be set to cut a chip having the full diameter of the hole to be bored, while the shorter blade *d* will be set so that its outer end is approximately 35 midway between the outer end of the shank blade *b* and the outer end of the longer blade *e*. When the parts are thus set, the following operation will take place in 40 boring a hole: The blade *b* will first remove a chip in advance of the engagement of the blade *d* with the wood, then the portion of the edge of the blade *d*, extending beyond the body of the auger, will next engage the wood, and will remove a chip having 45 a width corresponding to the distance which it projects beyond the blade *b* and having a thickness, or depth equal to the pitch of the thread *c*. The portion of the blade *e* which extends beyond the end of the path of the 50 end of the blade *d*, will next engage the wood and remove a similar chip, having a diameter equal to the diameter of the hole, but the wood which would have been otherwise removed by the edge-portion within 55 the path of the end of the blade *d* will have been removed by the latter, so that the chip removed by blade *e* will be of no greater width than the distance from the path of the end of the shorter blade to the path of 60 the end of the longer blade. The strain of boring which is placed on the blades is thus equalized to such an extent that neither blade *d* or *e* has an undue strain placed thereon. The danger that the longer blade 65 will be broken when boring a large hole is

thus to a large extent avoided, and, as the strains are nearly equalized, at opposite sides of the shank, there will be but slight tendency to prevent the bit from running true.

In practice three or more bits, all of different lengths, but all interchangeable, may be provided, so that the advantages of the above described construction may be secured in boring a hole of comparatively small diameter, as well as in boring one of large diameter, this being accomplished by employing the blade of intermediate length in the seat for the shorter blade, if a hole of large diameter is to be bored, and in the seat for the longer blade, if a hole of small diameter is to be bored, the longest blade being used, in the first instance, and the shortest blade, in the second, in the other seat. By arranging the cutting edges of the blades 70 so that the edge of the longer blade is farther removed from the path of the fixed blade, than the edge of the shorter blade, only by approximately the distance between the threads of the worm, I am able to satisfy all the requirements of an ordinary expansive bit, or wood auger, while at the same time, I make it possible to bore holes of 75 much greater diameter than may be bored with any other expansive bit, or wood-auger 80 of which I am aware, and, other conditions being equal, to do this without increasing the danger of the blades being broken by undue strain.

I claim:—

1. A wood auger comprising a shank having a feeding worm at its end, a pair of blades mounted on said shank adjacent its worm and having their cutting edges extending therefrom to different radial distances, the blade extending to the shorter radial distance having its cutting edge arranged in advance of that of the other blade by approximately the distances between two 100 of the threads of the worm.

2. A wood auger comprising a shank having a feeding worm at its end, a pair of blades mounted for radial adjustment on the shank with their cutting edges extending from points adjacent the end of the shank to different radial distances, the blade of shorter radius being disposed sufficiently in advance of the other blade to remove the chip which would otherwise be removed by the corresponding portion of the longer 105 blade.

3. A wood auger comprising a shank having a feeding worm on its end, a pair of blades mounted for radial adjustment on opposite sides of the shank and having their cutting edges extending from points adjacent the end of the shank to different radial distances, the blade of shorter radius having its cutting edge disposed sufficiently in advance of the corresponding portion of the 110

other blade to prevent operative engagement of such portion with the work.

4. A wood auger comprising a shank having a fixed blade and a feeding worm at its end, a pair of blades mounted for radial adjustment on opposite sides of the shank and having their cutting edges extending radially and obliquely from points adjacent and above the path of said fixed blade, approximately to the plane of said path, one of said blades extending to a substantially less radial distance than the other and having its cutting edge disposed sufficiently below the path of the corresponding portion of the other blade to prevent operative engagement of said portion with the work.

5. A bit-shank having a blade at its end and transverse blade-receiving grooves at opposite sides, clamping plates arranged to engage corresponding sides of said grooves, blades arranged to be engaged at opposite

edges by said plates and by the opposite sides of said grooves, and a clamping screw arranged to draw said plates into clamping engagement with said blades.

6. A bit-shank having a blade at its end and transverse blade-receiving grooves at opposite sides, clamping plates arranged to engage corresponding sides of said grooves, blades arranged to be engaged at opposite edges by said plates and by the opposite sides of said grooves, a clamping screw extending through one of said plates and said shank, and threaded in the other plate, to draw said plates into clamping engagement with said blades to lock them in said grooves.

In testimony whereof, I have signed my name to this specification.

HENRY O. DAVIS.
